UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S BASQUE.

SPECIFICATION forming part of Design No. 14,917, dated March 25, 1884.

Application filed February 13, 1884. Term of patent 3½ years.

To all whom it may concern:

Be it known that I, CATHERINE O'HARA, of the city, county, and State of New York, have invented and produced a new and original Design for a Pattern of a Lady's Basque, (numbered 9,120;) and I do hereby declare that the engraved prints accompanying this specification convey to any one accustomed to using paper patterns a clear understanding of how a garment made up by the pattern will appear.

The design shows closely-fitted fronts, curving away below the closing, and falling in short panniers that display draping-plaits in their back edges; a closely-fitted back, falling in two

deep, full points, and exhibiting fullness at the lower ends of its middle three seams, and a shirring at the center of its skirt; coat-sleeves, and a standing collar.

What I claim as my invention, and desire to secure by Letters Patent, is—

The design for a lady's basque, as shown in the engraved prints accompanying this specification.

CATHERINE O'HARA.
